BREECH DEVICE FOR FIREARMS

Josef Koucký, Prague, Bohemia; vested in the
Alien Property CustodianApplication March 8, 1941, Serial No. 382,429
In Bohemia and Moravia December 22, 1939

4 Claims. (Cl. 42—16)

The present invention relates to a breech device for firearms especially for those of smaller caliber, whether it be a repeater, an automatic or semi-automatic firearm. The present invention relates to a breech device for such firearms in which projectiles of a greater force of percussion, that is, cartridges developing a greater initial pressure and having a higher speed of firing are used.

This object is attained according to the present invention by this that there is arranged in the firearm a breech device characterised by a breech block forming a body having flat sides and tiltable around the longitudinal axis of the firearm and provided with locking lugs which engage in notches in the casing of the firearm. The breech block forms an appropriate quadri-lateral prism the base of which has a greater length than height and which is chamfered along a shorter length than the length of the body on the opposite parallel side-walls by parallel planes. Without counting that the arrangement according to the present invention considerably diminishes the height of the casing and thus also the weight of the firearm, a more advantageous formation of the breech block with regard to a more favourable straining by the pressure of the gases produced in firing the cartridges, is obtained. Thus it is also possible to use cartridges with a greater powder charge and therefore also a more violent force of percussion.

The accompanying drawing shows the arrangement of the device according to the present invention in two modifications. In Figs. 1 to 4 is shown the arrangement in the case of a hand operated firearm, which in Fig. 1 shows the longitudinal section of the breech block closed. Fig. 2 is a perspective view of the breech casing with the breech block open. Figs. 3 and 4 are transverse sections of the firearm following the lines III—III and IV—IV of Fig. 1.

Another example of the arrangement of the breech device in an automatic gas operated firearm is perspective shown in Fig. 5.

The firearm shown in Figs. 1 to 4 consists essentially of the barrel 1, which is fixed to the casing 2 of the breech by means of a screw thread; 3 is the front part of the stock, 4 is the upper part of the stock. In the under side of the casing 2 is arranged in a known manner the cartridge chamber 5 with the follower 6 charged with the spring 7. The trigger mechanism 8 is of a known construction and sets the hammer 9 in action. On the rear part of the casing 2 is fixed the butt 10. In the casing 2 of the breech moves

the breech block 11 with the striker 12 charged with a spring 12' and the ejector 13.

The breech block 11 has the shape of a flat slab with its bottom and top faces chamfered or beveled at 14, 14' outwardly from approximately the center longitudinal line of the face, the bevels being diagonally opposite, that is, the bevels of the top face being at the left of the center line and that of the bottom face at the right as seen in Fig. 2. The bevels extend from the rear end of the block forward a distance equal to the length of the arrow L in Fig. 2. The angle of bevel is indicated by α which is preferably from 15° to 30°. The forward end of the block is un-beveled and forms locking lugs 15, 15' adapted to be received in recesses 17, 17', respectively in the bottom and top wall of the case 2. The remaining portions of the top, bottom, and side wall of the casing form planes for guiding the breech block in executing the movement by which 10 the breech block passes into the closed or open position. It will be seen that the lugs 15, 15' have diagonal locking faces 16, 16' which engage rear end walls of the recesses 17, 17', respectively, when the block is tilted through the angle α into locked position. The lug 15 bears the bolt lever 18, which passes through a longitudinal slot in the casing 2 of the breech device, which ends in the locked position in a transverse slot 20, enabling the transverse motion of the bolt lever when locking the breech block.

When firing the breech block is located in the position shown in Fig. 4, when the lugs 15, 15' engage in the recesses 17, 17' and the breech block rests on both walls 14, 14' on the upper and under guiding walls inside the casing. The back pressure of the propellant gases that acts at the moment of firing on the center of the breech block is taken up by the plane faces 16, 16'. 20 Assuming that the reaction pressure on the casing has the same effect as it would if all concentrated at the centers of gravity of the two diagonal planes, it will be seen from Fig. 4, that the reaction pressure in effect will be concentrated on two points, a distance x apart and will be within the contour of the breech block body. This distribution of force or strain is much more favorable than in known breech block cylinders. The strain or distribution of force is 30 much more favorable because the bearing length is shorter and therefore under the same conditions the breech block may be more charged respectively stronger and more explosive charges may be used.

After firing the rifleman swings round the

bolt lever together with the breech block from the position shown in Fig. 4 into the position shown in Fig. 3 at the angle α disengaging the lugs 15, 15' and the recesses 17, 17' so that by pulling back the bolt lever the breech block can be brought to the open position. During this movement the empty cartridge case is pulled out in a known manner and at the end of the movement ejected from the casing 2 and at the same time the firing mechanism is tensioned. By the forward movement of the breech block a new cartridge 21 is brought into the cartridge chamber and after having accomplished the locking movement the breech block is swung round at the locking angle α . As it is quite sufficient if the locking angle is about 15 to 30°, the movement of locking and unlocking requires much less time than in the devices up to now in which it has been generally necessary to swing round the breech block by 90°. This fact increases the speed of firing which in modern firearms is one of the most important requirements.

According to the invention the breech block may also be used in automatic firearms as may be seen in Fig. 5 in which is shown a perspective view and a fragmentary section of a gas operated firearm.

The firearm shown in the drawing consists of the barrel 1, the casing 2' for the breech, in which the breech block 11, which is constructed in quite the same manner as that in the preceding case, is movably located. The breech block is again chamfered at the two opposite edges where the chamferings 14, 14' begin also at approximately a central longitudinal vertical plane through the prismatic body of the breech block. For actioning and governing there is a stud 22 fixed on the locking lug 15 which engages into the slot 23 at the end of the piston rod 24, whilst the piston 25 of the piston rod reaches into the gas cylinder 26 and is guided in a known manner in the casing 2 of the breech device. The gas cylinder is tightly fixed to the barrel by means of a sleeve 27. The forward movement of the breech device is assured by the buffer spring 28. The governing groove is chosen so that at the first shock of the gases on the piston the breech block remains still closed during a certain time and only when the piston 25 after having travelled through a certain distance leaves the

gas chamber, it is when the projectile has left the barrel, through the effect of the curved part of the slot 23 a swinging of the breech block 11 around the locking angle α takes place. After the unlocking has taken place, the piston rod 24 brings the breech block 11 into the rear end position. For operating the breech by hand a handle 29 is formed on the piston rod.

The executions described are given only by way of example and may be varied in details without departing from the scope of the invention especially as far as the governing of the breech block and the like are concerned.

What I claim is:

- 15 1. In a breech block device, a casing, a breech block slidable in said casing and guided by walls thereof, said block having opposite flat sides each formed with a bevel extending along part of the length of the side and extending outwardly from a line located approximately centrally of its width, the unbeveled portions beyond the ends of the bevel forming locking lugs and said casing being formed with recesses adapted respectively to receive said lugs and means for turning said block from an unlocked position in which the unbeveled portions of said sides are in guiding contact with said walls to a locked position in which said lugs are received in said recesses.
- 20 2. A breech block device according to claim 1 wherein, the block is in the form of a flat slab with top and bottom faces beveled and of greater area than the remaining faces of the block and wherein the bevels extend forward from the rear end of the block and the lugs are located at the front end.
- 25 3. A breech block device according to claim 1, wherein the block is in a form of a flat slab with top and bottom faces beveled and of greater area than the rear faces of the block, and wherein the bevels extend forwardly from the rear end of the block and the lugs are located at the front end, and wherein the lugs have flat rear faces and the recesses flat rear walls, and wherein, in locked position said faces and walls are in facial contact.
- 30 4. A breech block device according to claim 1, wherein the face of the beveled portion makes an angle of 15° to 20° with the continuation of the unbeveled face.
